ISIDOR LESEM, OF WICHITA, KANSAS.

EXPLOSION-ENGINE.

1,272,683.

Specification of Letters Patent. Patented July 16, 1918.

Application filed August 2, 1916. Serial No. 112,793.

To all whom it may concern:

Be it known that I, ISIDOR LESEM, a citizen of the United States, residing at Wichita, in the county of Sedgwick and State of 5 Kansas, have invented a new and useful Explosion-Engine, of which the following is a specification.

This invention has reference to explosion engines and its object is to provide an engine by means of which the direct effect of the explosion is utilizable for the propulsion of vessels on the water by the reaction of the effect of the explosion upon the water in which the vessel floats.

15 In accordance with the present invention the force of the explosion is exerted directly upon a movable member in contact with the water, so that the member moves against the water in the same direction as the force 20 of the explosion is exerted. This is brought about by providing a cylinder and piston constructed in accordance with gas engine practice, and connected to the piston is a movable member in the general form of a 25 piston mounted to act in the same direction as the first piston and by engagement with the water in which the vessel floats propel the vessel. By this means the force of the 30 explosion is directly transmitted to the water without the interposition of gearing or cranks or propeller wheels or the like. Moreover, by mounting the engine upon a swivel support it may be directed variously 35 to steer the vessel, or when the engine is mounted near the bow of the vessel the propelling force may be so directed as to lift the bow of the vessel so that the vessel in its movements operates after the manner of a glider.

40 Furthermore, the arrangement is such that the exhaust of the engine is utilized for propelling purposes and the pressure of the water upon the propelling member serves to return the parts to the first position, thus 45 compressing an explosive charge to be ignited after compression for consequent explosion, the action being automatic so long as an operator may desire.

The invention will be best understood 50 from a consideration of the following detailed description, taken in connection with the accompanying drawings forming part of this specification, with the further understanding that while the drawings show 55 a practical form of the invention, the latter

is not confined to any strict conformity with the showing of the drawings, but may be changed and modified so long as such changes and modifications come within the scope of the appended claims.

60

In the drawings:

Figure 1 is a side elevation with some parts in section of an engine embodying the present invention and showing a support whereby it may be attached to a boat so that 65 its propelling member may be located beneath the surface of the water.

Fig. 2 is a vertical axial section of the engine of Fig. 1.

Fig. 3 is a plan view of the engine of Fig. 70 1 showing it turned at an angle for steering purposes.

Fig. 4 is a schematic plan view of a boat equipped with a plurality of engines.

Referring to the drawings there is shown 75 a base 1 mounted to turn upon a support 2, the showing being more or less schematic and without attempt to illustrate any special structure. By swiveling the base 1 upon the support 2 the base may be turned to various angles assuming that the support 1 is approximately horizontal, or the support 1 may be assumed to be movable to various angles, so that the structure is capable of being moved toward various points on the 80 horizon or to various inclinations to an upright line. In the showing of Fig. 3 the support 2 may be considered either as horizontal or vertical, thereby illustrating the 85 various angular positions of which the engine is capable.

90 Mounted on the base 1 are standards 3, 4, respectively, carrying between them cylinders 5, 6, respectively. The cylinder 5 constitutes the power cylinder, while the cylinder 6 is utilized as a pump cylinder, and in the machine as built for active service these cylinders are properly proportioned to the work they are called upon to do. Within the cylinder 5 is a piston 7 mounted on a 95 piston rod 8 extending through the standard 3 and into a casing 9 in which is lodged a piston 10 constituting the driving member 100 of the engine and designed to engage the water in which the vessel floats for impact 105 thereon to drive the vessel. The cylinder 9 has a continuation 11, which since it need not be of as large size as the cylinder 10 is contracted toward the standard 3 and is connected to a base plate 12 made fast to the 110

standard 3. Mounted on the piston rod 8 is a spring 13 which serves the purpose of a shock absorber to prolong the effect of the explosion.

5 The cylinder 6 contains a piston 14 on a piston rod 15, which at the end remote from the piston is carried to the front of the cylinder 9 and made fast to the piston 10, so that each time the piston 10 reciprocates the piston 14 participates in such movement.

10 The cylinder 5 is provided with an intake valve 16, while the cylinder 6 has an intake valve 17 and an outlet valve 18. The cylinder 5 is provided with an exhaust outlet 19 opening toward the cylinder 9 and normally closed by a valve 20, which, however, is responsive to the force of the exhaust so as to allow the latter to escape into the water in a manner to aid in propelling the vessel.

15 20 The various valves 16, 17 and 18 are under the control of a lever 21, which in turn is operated by a rod 22 connected to the piston 10.

25 The lever 21 is mounted upon and turns about a pivot 21^a parallel with the length of the lever, so that the latter moves about a substantially horizontal arc when the parts are in the upright position shown in Figs. 1 and 2. This causes the twisted ends of the 30 lever to move in arcs about a substantially upright axis under the assumption that the engine is located as in Figs. 1 and 2, wherefore such arc of movement causes the actuation of the valves 16, 17 and 18, which action 35 is in proper sequence, considering the parts to be all properly adjusted.

40 The connection between the lever 21 and the pivot 21^a is through an angle bracket to one arm of which a lever 22^a is connected, this being a lever of the first class in the showing of the drawings. The lever 22^a is actuated by the rod 22, which in turn is actuated by the piston 10. Assuming the parts to be in the position shown in Figs. 1 45 and 2, and an explosion to have just taken place driving the piston 7 outwardly, the rod 22 connecting the piston 10 with the lever 22^a causes the movement of the lever 21 about an upright axis, and this by reason 50 of the twist of the ends of the lever permits the valve 16 to close and the valve 17 to open, so that the travel of the piston 14 with the piston 10 draws a fresh charge into the cylinder 6, while the outward stroke is taking 55 place. At the end of the outward stroke, the pistons 7 and 10 are returned to the first position by the pressure of the water on the piston 10, thereby again rocking the lever 21 on an upright axis, causing the valve 17 to close and the valves 16 and 18 to open, so 60 that the piston 14 having already drawn a charge into the cylinder 6, compresses this charge into the cylinder 5 in the explosion chamber thereof, ready for ignition when 65 full compression is reached.

The cycle of operations as described continues uninterruptedly so long as the engine runs.

70 For igniting the explosive mixture compressed in the cylinder 5, there is provided a spark plug 23 which is assumed to be connected to a source of electric current of proper character and to be operated in the manner usual in explosion engines to ignite the charges at proper time intervals. No 75 attempt is made to more than indicate the valves and operating mechanisms, because these may follow the usual gas engine practice.

80 The valve end of the engine is inclosed in a casing 24 and the cylinders 5 and 6 are in an installed engine submerged, which is also true of the casing 24, so that all parts are at all times under the cooling influence 85 of the water in which the engine is located and overheating is completely avoided.

90 In the standard 4 are ducts 25, 26, the latter having a pipe connection 27 which may be assumed to lead to any suitable source of explosive mixture of which the carbureter 95 may be taken as an example, but which carbureter is not shown in the drawings. The duct 26 opens into the cylinder 6 through the valve 17 and the cylinder 6 discharges through the valve 18 into the duct 25 from 100 which a charge drawn into the cylinder 6 is directed through the valve 16 into the cylinder 5 to be there compressed by the piston 7 and finally ignited by a spark at the spark plug 23. When an explosion takes 105 place the piston 7 is driven toward the left as viewed in Fig. 2 with the piston 10 participating in such movement, and as this piston is submerged in the water in direct contact with the latter, the direct propelling force 110 of the explosion is imparted directly and in the same direction to the surrounding water by the moving piston 10. As soon as the 115 exhaust port 19 is reached, at which time the force of the explosion has been spent, so that on the escape of the gases of combustion through the exhaust valve 20, the pressure of water upon the piston 10 causes a return movement of the parts to the first position, this being sufficiently powerful to 120 eject the fresh charge drawn into the cylinder 6 by the forward movement of the piston 14 and cause its transfer through the duct 25 to the cylinder 5, where it is ultimately compressed on the explosion chamber side of the piston 7 and then ignited for a second explosion. In this manner the engine is caused to run with the forward or power stroke caused by the explosion and the return or compression stroke caused by 125 the external water pressure, the whole operation taking place without any cranks or gears or revolving propellers and the only work to be performed other than the propelling movements is that necessary to op- 130

erate the valves, which work is practically negligible.

In Fig. 4 there is shown a boat 28, the showing being purely schematic, and on the 5 sides of the boat are supports 2 which may be assumed to carry explosion engines of the character hereinbefore described. By providing a multiplicity of engines mounted to be turned in the proper direction and to the 10 desired degree of inclination, the boat may be propelled with great force and at great speed with the forward engines so situated as to exert a lifting force, whereby water friction on the boat is largely eliminated. 15 An operator may control all the engines, and thereby be able to direct the boat by regulating the running of the engines on the opposite sides. For instance, if the boat is to be turned rapidly, the engines on one side 20 may be stopped and those on the other side permitted to run, or if the boat is to be turned slowly, these engines may be caused to run at different speeds without materially reducing the speed of the boat. 25 With the engine of the present invention power is applied directly, that is, in a straight line, from the explosion engine to the point of utilization, which in this case is the body of water in which the vessel floats, 30 this being done without cogs, or wheels or gearing of any kind, thereby eliminating a large amount of friction and acquiring a corresponding increase of power or efficiency. There is a further economy in utilizing 35 the pressure of water in the body of water in which the vessel floats for the return of parts to compress a new charge and operate the valves. Furthermore, what power may exist in the exhaust and which has 40 heretofore been to a large extent wasted, is directed so as to impact with the water in a manner to aid in propelling the boat.

By arranging the engine so that it may be swung about a vertical axis or tilted about 45 a horizontal axis, not only may the boat be steered but the lifting of the boat causes less displacement with a commensurate gain in power or speed without detracting from the efficiency of the engine.

50 Because the normal pressure of the water is utilized to return the parts to their first position, it is possible to secure a power stroke at every reciprocation without the use of wheels or other direction changing 55 means or extra cylinders or extra machinery of any kind.

By providing a sufficient range of turning movement of the engine it may be made to work in a direction opposite to the ordinary 60 propelling direction, whereby the boat may be readily moved backward or may be made by a lesser amount of deviation of the engine to turn within a very small radius.

While the drawings show and the description has referred only to one power cylinder,

it will be understood that each engine may include as many power cylinders as may be found necessary. In small boats a one-cylinder engine placed about midway of the width of the boat and toward the stern 70 thereof will be sufficient. With large boats each engine may be a multi-cylinder engine and as many engines are employed as the size of the boat and the speed desired may demand. 75

Again, the mounting of the engine so that it may be turned in various directions is susceptible of many embodiments, for which reason only one simple form has been shown, and such form has been to an extent schematically shown. 80

What is claimed is:—

1. An explosion engine for boat propulsion, comprising a cylinder and a reciprocatory piston therein adapted to be located 85 in the water on which the boat is supported, with the face of the piston directly exposed to the water, and a reciprocatory explosion engine having a piston directly connected with the first-named piston, with the connection yieldable in the direction of the movement of the pistons to absorb the shock of the explosion in transmitting the movement of the second piston to the first-named piston. 90

2. An explosion engine comprising a cylinder, a reciprocatory piston therein, means for propelling the piston by explosive forces, a water-engaging member connected to the piston for reciprocation thereby to the same 100 extent and in the same direction as the piston, and connecting means between the piston and the water-engaging member yieldable in the direction of the stroke to cushion the effect of the driving impulse due to the 105 explosion upon the water-engaging member.

3. Boat propelling means, comprising a power unit having a reciprocatory piston with means for driving it by explosive impulses, a water engaging piston in line with 110 the first-named piston and movable thereby in the same direction and to a like extent as the power piston, and a mounting for the power unit and the water engaging piston for the simultaneous and bodily adjustment 115 of both the power unit and the water-engaging piston for adjusting the direction of movement of the parts with respect to the direction of movement of the boat through the water. 120

4. An explosion engine for boat propulsion, comprising an explosion cylinder with a piston therein, another cylinder with a piston therein, said second cylinder having one end open for contact of the piston therein with the water on which the boat floats, a piston rod carried by the first-named piston and engaging the second-named piston, and cushioning means between the piston rod and second-named piston and constituting a 130

shock absorber for relieving the second-named piston from the sudden effect of an explosion acting on the first-named piston.

5. An explosion engine for boat propulsion, comprising an explosion cylinder with a piston therein, another cylinder with a piston therein connected to the piston of the first-named cylinder, said second cylinder having one end open for contact of the piston therein with the water on which the boat floats, and valve mechanism and a valve casing for the engine, whereby the whole engine may be immersed in the water on which the boat floats for the propulsion of the boat by reciprocation of the second-named piston, said engine having a shock absorber interposed between the two pistons, and said engine also being provided with an exhaust duct for the explosion cylinder opening into the water in a direction corresponding to the power stroke of the second-named piston.

6. Means for boat propulsion, comprising an explosion engine with a power piston, another piston connected to the first-named piston for actuation thereby in the same direction and to a like extent, means for forcing explosive charges into the first-named

piston, and connections between the second-named piston and said last-named means for actuating said last-named means by reciprocation of the second-named piston.

7. Means for boat propulsion, comprising an explosion engine with a power piston, another piston connected to the first-named piston for actuation thereby in the same direction and to a like extent, means for forcing explosive charges into the first-named piston, and connections between the second-named piston and said last-named means for actuating said last-named means by reciprocation of the second-named piston, said explosion engine being provided with valves and actuating means therefor, and connections between the valve actuating means and the second-named piston for the operation of the valve operating means by reciprocation of the second-named piston.

In testimony that I claim the foregoing as my own, I have hereto affixed my signature in the presence of two witnesses.

ISIDOR LESEM.
